EXCAVATING MACHINE

Hubert Hollmann, River Forest, Ill., and William G. Van Voorhis, Columbus, Ohio, assignors to The Buckeye Traction Ditcher Company, Findlay, Ohio, a corporation of Ohio

Application July 8, 1943, Serial No. 493,831

4 Claims. (Cl. 37—97)

This invention relates to excavators, but more particularly to wheel type ditchers or trenchers equipped with a digging wheel which when in operation, excavates a trench or a ditch as the machine advances, the digging wheel being above the surface of the ground when not in use.

Machines equipped with wheel type excavators are ordinarily mounted for vertical translatory movement along upright elevator rails which are fixed to the rear end of the machine frame. Ordinarily, these rails are rigidly braced to the main frame of the machine in order to make them sufficiently rigid and these braces are objectionable because they obscure the vision of the operator who takes care of the advancing movement of the machine. In order to militate against the disadvantage caused by lack of vision, many machines of this character are equipped with separate controls at the rear of the machine so that when the machine is excavating, the operator can change his position to be closer to the digging wheel and enable its operation to be more closely observed.

An object is to overcome the above difficulties and to produce a machine of this character in which the elevator rails are supported in a new and improved manner without the use of the usual sight-obscuring braces.

Another object is to produce a frame construction for wheel type trenchers having the new and improved features of construction and arrangement hereinafter described.

A further object is to produce a frame structure for a wheel mounted trencher equipped with a digging wheel which affords greater visibility to the operator in normal traveling position so that the operator can assume the same position whether for traveling or for excavating.

Other objects and advantages of the invention will hereinafter appear and for purposes of illustration but not of limitation, an embodiment of the invention is shown in the accompanying drawings in which

Figure 1 is a diagrammatic side elevation of a wheel mounted trenching machine equipped with a digging wheel and showing the latter in excavating position;

Figure 2 is an enlarged side elevation of the frame structure for the machine diagrammatically showing a portion of the traction and digging wheel drives;

Figure 3 is an enlarged end elevation of the frame showing the elevator construction and the positioning of the digging wheel and traction drives; and

Figure 4 is a fragmentary top plan view of the main frame and elevator structure.

The illustrated embodiment of the invention comprises a trenching machine which has a main frame A which is mounted upon front wheels B and rear tandem wheels C, two of which are disposed on each side of the vehicle. Mounted at the front end of the main frame and extending forwardly of the front or steering wheels 10 B is a suitable power plant D which is suitably connected for driving the drive or tandem wheels for propelling the machine along the ground. Since the operative connections between the power plant D and wheels C form no part of the present invention, detailed description and illustration thereof is not considered necessary.

Intermediate the wheels B and C, is the operator's position E convenient to the steering wheel F and both the traction and digging controls. Carried at the rear end of the machine is a digging wheel G equipped with a series of excavating buckets H (only one of which is shown). It will be readily understood by those skilled in this art that the buckets H successively 20 dig into the ground and elevate the dirt or spoil to a position where it is discharged upon a conveyor J discharging the same laterally of the machine. The construction and operation of the digging wheel G is old in the art and detail description thereof is not considered necessary since it forms no part of the present invention.

As will hereinafter be more fully described, the elevator structure K is secured to the rear end of the main frame A and the frame of the digging wheel G has slides L which ride vertically along the elevator rails and vertical movement is imparted to the digging wheel by suitable cables M which extend to the rear end portion of the digging wheel frame, and N which connect to the forward end of the digging wheel frame. These cables extend forwardly over sheaves generally designated at O and thence downwardly to suitable power winches P mounted on the main frame A and deriving power from the power plant D.

Through suitable connections, the power plant D operates through differential mechanism Q to drive the digging wheel G through suitable sprocket and chain connections R. Likewise, the power plant D drives through suitable connections a differential S which is operatively connected to the tandem drive wheels C. The differential S is disposed beneath the differential Q and the mounting and arrangement of these

differentials and drives will hereinafter more fully be described.

The main frame includes a pair of side beams 10 which are of channel construction and in this instance, a forward extension 10a fits in the front end portion of the beam 10 and is fixed in place in any suitable manner as by welding. If desired, however, instead of a fabricated beam, the beam could be of a one piece. As indicated the beam 10 is gradually enlarged to a point 11, the upper edge being substantially horizontal wherein the lower edge inclines downwardly thereby gradually thickening the beam to the region 11 which is spaced forwardly of the elevator rail structure K. From the point 11 the beam inclines upwardly forming with the horizontal portion of the beam, an obtuse angle. This upwardly inclined beam portion 12 terminates in an up and down contact face 13 which is disposed at substantially right angles to the horizontal.

The lower edge portion of the upwardly inclined portion 12 terminates in a horizontal portion 14 which is substantially parallel to the upper edge of the beam portion 10. It will be apparent that the upwardly inclined portion 12 from the bend to the up and down contact face 13 provides a very strong and sturdy support and engaging the contact face 13 is an elevator rail 15 which forms part of the elevator rail structure K. The rail 15 is likewise of channel construction and a flange of the elevator rail 15 is secured to the flange forming the contact face 13 by a series of bolt and nut assemblies.

The elevator rail 15 projects above and below the contact face 13, the longer portion projecting above this face. As indicated in Figure 3, there are two upright elevator rails 15 similarly connected to side beams and the lower portion of these rails are secured together by a cross beam 16 which may be welded to the rails and triangular shaped plates 17 are welded on both sides of the cross beam 16 to the adjacent rails 15 respectively. Near the top of the rails extends a cross beam 18 which may be welded to the rails and projects slightly beyond the sides thereof. Substantially U-shaped cages 19 extend over the upper ends of the elevator rails 15 and mounted on shafts carried thereby are the sheaves O above mentioned. Triangular shaped braces 20 brace the top beam 18 to the elevator rails 15 as shown.

It will be understood that several cross bars or beams 21 are secured at their ends to the side beams 10 in order to provide a rigid structure and at the front end a beam 22 is connected to the spaced side beams.

Fixed as by welding to the inside of each upwardly inclined beam portion 12 is a horizontally disposed shelf bracket 23 and rising from the rear end portion of each shelf bracket 23 is a bracket plate 24 having a rearwardly extending web 25. The shelf bracket 23 and plate 24 provide the support to which a suitable bracket may be bolted. Such bracket supports the end portions or tubular casing for the digging wheel differential drive Q. As shown, each upwardly inclined beam portion 12 is formed with an opening 27 through which extends the differential shaft and the trunnion and sprocket assembly carried by the end portion thereof.

Rigid with the outer side of each upwardly inclined beam portion 12 is a rib or bracket shelf 28 arranged beneath the opening 27. Bolted to the underside of the bracket shelf 28 and also to the depending portion of the adjacent elevator rail 15 is a plate 29, to the inside of which the

adjacent portion of the traction differential S may be suitably secured. As shown, the shelf bracket 28 is formed with suitable ribs 30 and 31 for affording the desired strength and rigidity.

From the above description, it will be manifest that the elevator rail structure K is rigid with the main frame and is sufficiently strong and sturdy to accommodate the weight of the digging wheel G when the latter is elevated to traveling position, as well as to support the same in proper relation to the machine during excavating. The entire structure and assembly is so designed as to eliminate sight-obscuring braces heretofore employed for bracing the elevator rail structure K with respect to the main frame. Not only does the frame structure have the desirable functional utility as mentioned above, but it also greatly enhances the appearance of the machine.

Numerous changes in details of construction, arrangement and operation may be effected without departing from the spirit of the invention especially as defined in the appended claims.

What I claim is:

1. An excavating machine comprising a main frame, a traction support for said main frame, a power plant at the front end portion of said main frame, a digging wheel disposed rearwardly of said main frame, mechanism for driving said traction unit from said power plant, mechanism for driving said digging wheel from said power plant, operating means for said mechanisms disposed intermediate the ends of said frame, said main frame including side beams having enlarged rear end portions providing up and down rear end faces, upright elevator rails fixed to said end faces and projecting above and below same, each of said enlarged rear end portions having an aperture through which extends a portion of said digging wheel driving mechanism, a shelf beneath each aperture, and a bearing bracket for said digging driving mechanism on each shelf.

2. An excavating machine comprising a main frame, a traction support for said main frame, a power plant at the front end portion of said main frame, a digging wheel disposed rearwardly of said main frame, mechanism for driving said traction unit from said power plant, mechanism for driving said digging wheel from said power plant, operating means for said mechanisms disposed intermediate the ends of said frame, said main frame including side beams having enlarged rear end portions providing up and down rear end faces, upright elevator rails fixed to said end faces and projecting above and below same, each of said enlarged rear end portions being upwardly inclined and having an aperture through which extends a portion of said digging wheel driving mechanism, a shelf beneath each aperture, a bearing bracket for said digging driving mechanism on each shelf, and said upwardly inclined rear end portions accommodating said traction unit driving mechanism.

3. In an excavating machine, a main frame including a pair of longitudinal side beams, each side beam including a substantially horizontally disposed portion, an integral upwardly inclined rear end portion, a vertically disposed elevator rail in abutting and fixed relation to the rear end of said upwardly inclined end portion, a portion of said elevator rail projecting above and another portion below said end portion, each upwardly inclined portion having an aperture to enable drive shaft to project therethrough, a shelf

on each beam beneath said aperture, and a bearing bracket fixed to each shelf.

4. An excavating machine comprising a main frame, a traction support for said main frame, a power plant at the front end portion of said main frame, a digging wheel disposed rearwardly of said main frame, mechanism for driving said traction unit from said power plant, mechanism for driving said digging wheel from said power plant, operating means for said mechanisms disposed intermediate the ends of said frame, said

main frame including side beams having enlarged rear end portions providing up and down rear end faces, upright elevator rails fixed to said end faces and projecting above and below same, each 5 of said enlarged rear end portions having an aperture through which extends a portion of said digging wheel driving mechanism, and means associated with each aperture providing a bearing for said digging wheel driving mechanism.

HUBERT HOLLMANN.

WILLIAM G. VAN VOORHIS.
